(57) **CLAIM**

The ornamental design for a drying shelf, as shown and described.

DESCRIPTION

FIG. 1 is an upper front perspective view of a drying shelf showing the new design;

FIG. 2 is a lower rear perspective view of the drying shelf of FIG. 1;

FIG. 3 is a front elevation view of the drying shelf of FIG. 1;

FIG. 4 is a rear elevation view of the drying shelf of FIG. 1; FIG. 5 is a left side elevation view of the drying shelf of FIG. 1;

FIG. 6 is a right side elevation view of the drying shelf of FIG. 1;

FIG. 7 is a top plan view of the drying shelf of FIG. 1; FIG. 8 is a bottom plan view of the drying shelf of FIG. 1; and,

FIG. 9 is an illustration of the claim in a use of environment of the drying shelf of FIG. 1.

This disclosure encompasses one or more embodiments which may, for example, include one or more movable accessories such as shown in FIGS. 1 (e.g., the folding dry rack folds into three units).

The broken lines (dash-dash) shown in the drawings illustrate portions of the article and form no part of the claimed design. Where no boundary line is shown between the solid and broken lines, it is to be understood a boundary line connects the ends of solid lines to demarcate a boundary between claimed portion and an unclaimed portion. Dash-dot-dot-dash lines indicate illustrative environment in which the design may be used and form no part of the claimed design.
